MICROWAVE SCANNING SYSTEM AND
METHODGeorge L. Fernsler, Lawrenceville, N. J., assignor
to Radio Corporation of America, a corpora-
tion of Delaware

Application July 31, 1947, Serial No. 765,037

13 Claims. (Cl. 250—33.65)

1

This invention relates generally to microwave propagation systems and methods and more particularly to improved methods of and means for changing the azimuth or elevation angle of a parabolic microwave antenna system without changing the physical position of the parabolic reflector.

It has been customary in microwave propagation systems to utilize a horn type or flared radiator type wave projector operating into a parabolic reflector which is employed primarily to improve the directivity of the radiated beam. For example, a rectangular waveguide system operating in the TE_{01} mode may be employed with a matching section preceding a horn wave radiator, the horn opening toward a transversely disposed plane reflector to project the radiated beam to a parabolic reflector which thereby improves the directivity of the radiating beam. In previously employed systems, the position of both the radiating horn and the beam reflector have been changed to provide variation of the elevation or azimuth angle of the propagated energy. Mechanical displacement of relatively large mechanical elements required in such systems is relatively difficult and expensive and requires considerable maintenance.

The instant invention contemplates an improved system for providing variable elevation or azimuth angle of radiated microwaves by changing the directivity of the microwave radiation prior to its projection toward the parabolic reflector structure.

In accordance with a first embodiment of the invention, an elbow of a matched section of waveguide opening into the horn radiator includes a wave reflecting element or diaphragm reflector, the position of which may be changed by the action of a solenoid or a mechanical actuating mechanism. Changing the position of the waveguide reflecting element changes the directivity of the microwaves radiated from the microwave horn, thereby changing the radiating beam projected from the parabolic reflector. Since movement of a wave reflecting element in a transmission waveguide structure causes variations in the impedance characteristics of the transmission waveguide, a tuning element preferably is included in the transmission waveguide and synchronized with the movable wave reflector to provide substantially constant microwave transmission characteristics.

The second embodiment of the invention employs a section of transmission coaxial line or waveguide, including microwave radiating ele-

ments, which is arranged to rotate in an arc with respect to the balance of the microwave coaxial line or waveguide transmission system. Thus a fixed parabolic reflector disposed adjacent to the movable wave radiating element will project a microwave beam through a variable angle in the plane of motion of the movable microwave radiator. A variable control element, such, for example, as a variable resistor, synchronized with the motion of the arcuately adjustable radiating element, controls a pair of solenoids which actuate electromagnetic tuning elements operable to interpose suitable reactance into the main transmission line to compensate for variations in the impedance of the line due to the arcuate motion of the radiating portion of the system.

Among the objects of the invention are to provide improved methods of and means for scanning a predetermined spacial region by microwave energy. Another object of the invention is to provide an improved method of and means for radiating a microwave beam through a predetermined elevation or azimuth angle. An additional object is to provide an improved method of and means for employing a relatively fixed parabolic wave reflector for radiating a variably directional microwave beam. A further object of the invention is to provide improved methods of and means for radiating a microwave beam through a variable elevation or azimuth angle by varying the directional characteristics of a microwave beam projected toward a relatively fixed parabolic microwave reflector. Another object of the invention is to provide improved methods of and means for radiating a microwave beam through a variable elevation or azimuth angle by varying the directional characteristics of a microwave beam projected toward a relatively fixed parabolic microwave reflector and including means synchronized with the variable directional radiating means for providing constant impedance characteristics in the transmission system.

The invention will be described in greater detail by reference to the accompanying drawing of which Figure 1 is a schematic circuit diagram of a first embodiment of the invention, Figure 2 is a schematic circuit diagram of a second embodiment of the invention and Figure 3 is a fragmentary schematic view of a modification of said first embodiment of the invention. Similar reference characters are applied to similar elements throughout the drawing.

Referring to Figure 1 of the drawing, a first embodiment of the invention utilizes a movable diaphragm wave reflector 1 at an elbow 3 of a

waveguide 5 connecting a microwave generator 1 to a microwave radiating horn 9. The mouth of the horn 9 faces a plane wave reflector 11 which reflects the radiated waves back to a parabolic reflector 13 which effectively focusses the radiated waves in a parallel beam 15. The movable reflector 1 is pivoted at the point 17 and may include a corrugated Sylphon bellows joint 19 on the opposite face thereof. The movable diaphragm reflector 1 is actuated by a solenoid 21 to which is applied a sawtooth or sine wave voltage derived from a scanning voltage source 23.

Movement of the diaphragm reflector 1 in response to the scanning voltage, as indicated by the arrow 25, changes the effective angle of the microwaves radiated from the mouth of the horn 9, thereby varying, either in a vertical or horizontal plane, the radiation angle of the focussed microwave beam 15. The device may be arranged to vary either the elevation or azimuth angle of the radiated microwaves, and if desired, two elbows and movable diaphragms may be employed to vary both angles in any predetermined pattern. The scanning pattern in either plane is determined by the wave form of the scanning voltage applied to the solenoid 21.

Movement of the pivoted diaphragm reflector 1 in the waveguide 5 varies the effective transmission impedance characteristics of the waveguide, thereby requiring that supplemental impedance matching means be provided. The transmission impedance characteristics of the waveguide may be matched at all times, regardless of the position of the pivoted reflector 1, by inserting a matching diaphragm 27 across the generator portion of the waveguide and by utilizing a transversely movable tuning plunger 29 adjacent to the matching diaphragm 27. The position of the tuning plunger on the transverse axis of the waveguide 5 may be controlled by a second solenoid 31 actuated in synchronism with the pivoted reflector 1.

The scanning voltage source 23 is connected through an amplifier 33 and a wave-shaping circuit 35 to energize the second solenoid 31 and thus actuate the tuning plunger 29 in desired phase and synchronism with the pivoted reflector 1. The wave-shaping circuit 35 is optional since it may be desirable to actuate the tuning plunger by the same type of scanning voltage waveform as actuates the movable reflector. However, if a different type of scanning voltage waveform is desired for actuation of the tuning plunger, the desired change in waveform may be provided by the wave-shaping circuit 35.

From the foregoing description, it is seen that the elevation or azimuth angle of radiated microwaves may be varied in any desired manner without moving any of the cumbersome microwave radiating or reflecting apparatus. The only movable elements required are a small light diaphragm forming one of the walls of the transmission waveguide structure and a tuning plunger synchronized with the movable diaphragm. It should be understood that the tuning plunger and pivoted reflector may be synchronized by purely mechanical linkages instead of by the electrical linkage described heretofore, and that other types of variable tuning devices may be substituted for the solenoid-actuated tuning plunger described.

Figure 2 illustrates a second embodiment of the invention wherein the microwave generator 1 is connected through a coaxial transmission line 5' to a dipole antenna 41. A plane reflector 11

and a parabolic reflector 13 provide suitable focussing of the radiated microwaves from the antenna 41 to provide a substantially parallel radiated microwave beam. A portion 43 of the transmission coaxial line 5' is pivoted at the point 45 so that the antenna and reflector structure may be scanned through an arc in the desired elevation or azimuth angle by an oscillating mechanical drive 47 operable upon the center conductor 49 of the rotatable transmission line section 43.

The oscillating center conductor 49 of the transmission line section 43 actuates the movable contact 51 of a variable resistor 53 to vary the voltage from a battery 55 applied to the input circuit of an amplifier 57. The output circuit of the amplifier 57 is applied to a pair of amplifier wave-shaping circuits 59, 61. The output circuits of the amplifier wave-shaping circuits 59, 61 are connected respectively to a pair of solenoids 63, 65 for actuating a pair of tuning plungers 67, 69 extending into the main transmission line 5'. Preferably the tuning plungers 67, 69 are separated by a distance of the order of $\frac{3}{8}$ wavelength at the operating microwave frequency in order that they may provide the desired reactive effect upon the transmission line to match the antenna to the microwave transmitter for all positions of the movable antenna system. A bearing contact 71 at the end of the inner conductor 73 of the main transmission line 5' provides suitable electrical contact between the main transmission line and the rotatable center conductor of the antenna transmission line.

If desired, the parabolic reflector 13 may be fixed with respect to the main transmission line 5', the antenna portion 43' of the movable portion of the transmission line being movable through the desired small elevation or azimuth angle in a slot 73 in the parabolic reflector 13. The plane reflector 11 would be movable with the antenna 41.

The embodiment of the invention described by reference to Figure 2 of the drawing utilizes a mechanical oscillating drive 47 as distinguished from the scanning voltage source 23 of the first embodiment of the invention described by reference to Figure 1. It should be understood that the amplifier shaping circuits 59, 61 should be properly designed, in accordance with known technique, to provide the desired electrical wave shape for actuating the tuning plungers 67, 69 in proper phase relation with movable antenna system so that the antenna is effectively matched to the microwave transmitter under all operating conditions.

Figure 3 illustrates a typical mechanical modification of the first embodiment of the invention, described heretofore by reference to Figure 1, wherein the movable diaphragm reflector 1 is coupled through a mechanical linkage to the tuning plunger 29. Movement of the diaphragm reflector 1 in the direction indicated by the arrow 25 causes the L bracket 75 pivoted at the points 77, 79 and 81 to move the tuning plunger 29 in the direction indicated by the arrow 83, thereby synchronizing the tuning plunger with the pivoted reflector. It should be understood that the mechanical linkage thus described is used merely for the purpose of illustration, and that various other types of linkages and/or cam arrangements may be substituted to provide the desired cooperation between the movable dia-

phragm and the tuning plunger or other tuning devices.

Thus the invention described comprises improved methods of and means for varying the radiation angle of a focussed microwave beam and for simultaneously and synchronously adjusting the microwave transmission characteristics between the microwave generator and directional antenna system to match the generator to the load under all operating conditions. The device 10 may be utilized to vary either the elevation or azimuth angle of the radiated microwaves. Either electrical or mechanical linkages may be provided between the microwave direction controlling element and the microwave tuning element to provide the desired cooperation therebetween.

I claim as my invention:

1. A microwave propagation system including an antenna system having variable directional characteristics, a microwave signal circuit coupled through a transmission line to said antenna system, means including a rotating joint supporting said antenna for varying said antenna directional characteristics, adjustable voltage means operable simultaneously in response to and in synchronism with movement of said antenna and with said variation of said antenna directional characteristics, and adjustable tuning means for said transmission line separate from said directional varying means and responsive to said voltage means for adjusting the microwave coupling between said circuit and said antenna system to compensate for resultant variations in the output impedance of said antenna system as said antenna directional characteristics are varied.

2. Apparatus according to claim 1 including amplifying and wave-shaping means responsive to said voltage means and actuating said tuning means.

3. Apparatus according to claim 2 including solenoid means responsive to said amplifying and wave-shaping means for actuating said tuning means.

4. Apparatus according to claim 3 wherein said tuning means comprises a plurality of reactive devices operable upon the field of said transmission line.

5. Apparatus according to claim 4 wherein said reactive devices are spaced distances of the order of three-eighths of the operating wavelength along said transmission line.

6. Apparatus according to claim 5 wherein said antenna system comprises a resonant structure focussed by a substantially parabolic reflector.

7. A microwave propagation system including an antenna system having variable directional characteristics, a waveguide transmission line, a microwave signal circuit coupled through said wave transmission line to said antenna system, means including a movable reflector in said line for varying said antenna directional characteristics, adjustable voltage means operable simultaneously in response to and in synchronism with movement of said reflector and said variation of said antenna directional characteristics, and adjustable tuning means for said transmission line separate from said reflector and responsive to said voltage means for adjusting the microwave coupling between said circuit and said antenna system to compensate for resultant variations in the

output impedance of said antenna system due to said movement of said reflector.

8. Apparatus according to claim 7 including a fixed diaphragm in said waveguide disposed between said tuning means and said reflector.

9. Apparatus according to claim 8 including solenoid means responsive to said voltage means for actuating said reflector and said tuning means.

10. Apparatus according to claim 9 including amplifying and wave-shaping means interposed between said voltage means and said tuning actuating means.

11. Apparatus according to claim 7 wherein said movable reflector and said tuning means are mechanically coupled and movable together.

12. A microwave propagation system including an antenna system having variable directional characteristics, a microwave signal circuit coupled through a transmission line to said antenna system, means for varying the directional characteristics of said antenna system, adjustable control means operable simultaneously in response to and in synchronism with said directional varying means, and adjustable tuning means for said transmission line separate from said directional varying means and responsive to said adjustable control means for adjusting the microwave coupling between said signal circuit and said antenna system to compensate for resultant variations in the output impedance of said antenna system as said antenna directional characteristics are varied.

13. A microwave propagation system including an antenna system having variable directional characteristics, a microwave signal circuit coupled through a transmission line to said antenna system, means for varying the directional characteristics of said antenna system, adjustable voltage means operable simultaneously in response to and in synchronism with said antenna directional varying means, and adjustable tuning means for said transmission line separate from said antenna directional varying means and responsive to said voltage means for adjusting the microwave coupling between said signal circuit and said antenna system to compensate for resultant variations in the output impedance of said antenna system as said antenna directional characteristics are varied.
